UNITED STATES PATENT OFFICE

113,701

DESIGN FOR A GAME BOARD

Forrest T. Bockemuehl, Harrisonburg, Va.

Application June 7, 1938, Serial No. 77,653

Term of patent 3½ years

To all whom it may concern:

Be it known that I, Forrest T. Bockemuehl, a citizen of the United States, residing at Harrisonburg, in the county of Rockingham and State of Virginia, have invented a certain new, original, and ornamental Design for Game Board, of which the following is a specification, reference being had to the accompanying drawing, forming a part thereof.

The game board forming the subject matter of this design includes a series of holes for the

use of pegs, the latter being used as in playing checkers.

In the drawing:

Figure 1 is a plan view of the game board, and

Figure 2 is a view in edge elevation thereof.

I claim:

The ornamental design for a game board, as shown and described.

FORREST T. BOCKEMUEHL.
